CAN OPENER

Wallace E. Cross, Detroit, Mich., assignor of one-half to John S. Murray, Detroit, Mich.

Application November 20, 1935, Serial No. 50,707

22 Claims. (Cl. 164—119)

This invention relates to container openers, and particularly to an improvement on the opener disclosed by U. S. Patent No. 1,996,550, issued April 2, 1935.

Sheet metal cans have to some extent replaced bottles as containers for beverages (and more especially beer) and it has been found a convenient method of opening such a can to pierce the top thereof, the tool disclosed in the aforementioned patent being well suited for that purpose. It is well known that beer and many other beverages release considerable gas unless maintained at a low temperature, and that such beverages are commonly under more or less super-atmospheric pressure, when in sealed containers. Consequently, when a can of beer is pierced, there is often a tendency for the beverage to spurt up with considerable force. The resulting waste of the beverage is objectionable, but much more serious is the possibility of damage to clothes and furniture.

It is an object of the present invention to equip a can-piercing tool with a guard or shield that will obstruct the path of any jet of liquid upwardly spurting from the pierced opening, and a further object is to so form such guard or shield as to avoid any lateral deflection of the jet.

Adaptation of the guard to undergo a limited up and down swinging movement on the can-piercing tool is a further object, the guard being thus permitted to maintain contact with a can top, as the piercing member is swung down within the can.

These and various other objects the invention attains by the construction hereinafter described, and illustrated in the accompanying drawing, wherein:

Fig. 1 is a top plan view of a can-piercing tool with attached guard.

Fig. 2 is a bottom view of the same.

Fig. 3 is a side elevational view thereof.

Fig. 4 is an elevational view, partially in section showing the tool in use.

Fig. 5 is a top plan view of the tool, showing an alternative construction whereby the guard is attached.

Fig. 6 is a side elevational view of the construction shown in Fig. 5.

Fig. 7 is a cross section taken on the line 7—7 of Fig. 6.

In these views, the reference character 1 designates a sheet metal can having a bead 2 outstanding from its wall at the juncture thereof with the can top.

55 A tool for piercing the can top comprises a

handle 3 having an approximately V-shaped end portion 4 bent downwardly at approximately one hundred and thirty-five degrees to the handle length, its point portion having a slightly increased inclination. At the base of the portion 4, there is struck out from said portion, centrally thereof, a relatively short tongue 5, which also forms approximately one hundred and thirty-five degree angle with the handle length. This tongue, when hooked under the bead 2 (see Fig. 3), establishes a fulcrum about which the tool may be swung to press the portion 4 strongly against the can top and pierce therein a V-shaped opening.

The present invention consists in applying to the described tool a guard 6, formed preferably of sheet metal, and so disposed above the portion 4 as to block any jet spurting upward from the pierced opening. Preferably such guard is circular and upwardly dished so as to overcome any tendency of the jet to deflect laterally. Said guard is preferably of a diameter considerably exceeding the width of the portion 4, projecting laterally and forwardly beyond said portion sufficiently to definitely prohibit any upward escape of liquid. The guard may be peripherally formed with a tongue 7 terminally welded or otherwise secured to the handle 3 near its juncture with the portion 4 (Figs. 1, 2, 3, and 4), or attachment to the tool may be effected by bending around the handle a pair of lugs 8, projecting laterally from the tongue 7 (Figs. 5, 6, and 7).

If the guard is welded or otherwise rigidly connected to the tool it is necessary that tongue 7 flex during piercing of a can, so that the portion 4 may swing down within a can, while the guard remains seated on the top thereof, this being clearly indicated in Fig. 4.

If the lugs 8 are employed to attach the guard to the tool, it is preferred to provide a space between the tongue 7 and the aligned lower portions of the lugs 8 sufficient to afford the guard such angular play as is necessary. By forming the handle edges with a pair of opposed notches 9 to receive the lugs 8, the guard may be definitely held in suitable proximity to the cutting portion 4 of the tool.

The described guard may be inexpensively stamped out of sheet metal in a single operation, and adds only slightly to the cost of the piercing tool. It fully eliminates the possibility of damage due to up-spurting of the beverage.

The invention is presented as including all such modifications and changes as come within the scope of the following claims.

What I claim is:

1. A container opener comprising a handle, a piercing member carried by an end portion of the handle and downwardly projecting in use, and a guard carried by the handle above the piercing member and proportioned to block any liquid jet upspurting from an opening formed by the piercing member.
2. A container opener comprising a handle, a piercing member carried by an end portion of the handle and downwardly projecting in use, and a guard carried by the handle above the piercing member, and proportioned to block any liquid upspurting from an opening formed by the piercing member, and angularly movable on the handle to maintain contact with a container top during downward actuation of the piercing member within the container.
3. A container opener comprising a handle, a piercing member carried by an end portion of the handle and extending forwardly and downwardly from the handle, and a guard attached to the handle at its juncture with the piercing member and projecting above the piercing member and forwardly and laterally beyond the piercing member to block any liquid upspurting from an opening formed by the piercing member, said guard being movable to assume various angular relations to the piercing member.
4. A container opener comprising a handle integrally formed with a piercing member extending forwardly and downwardly relative to the handle, a fulcrum member carried by the handle and operatively engageable with a container at the juncture of the container sides and top, and a guard projecting from the handle above the piercing member and extending laterally and forwardly beyond the piercing member to block any liquid upspurting from an opening formed by the piercing member.
5. A container opener comprising a handle terminally formed with a downwardly bent piercing member, a tongue downwardly struck from said handle adjacent to the piercing member and forwardly projecting to form a fulcrum member operatively engageable with an edge portion of a container, and a guard attached to the handle between said tongue and piercing member and projecting above the piercing member to block any liquid upspurting from an opening formed by the piercing member.
6. A container opener, comprising a handle integrally formed with a piercing member, a guard disposed above the piercing member to block any jet of liquid upspurting from the opening formed by the piercing member, and a tongue integrally projecting from the guard and having a terminal portion embracing the handle.
7. A container opener as set forth in claim 6, said terminal portion affording the guard an angular motion to and from the piercing member to permit the guard to maintain contact with the top of a container during downward actuation of the piercing member within the container.
8. A container opener comprising a handle, a piercing member carried by an end portion of and downwardly projecting from the handle, a fulcrum member carried by and downwardly projecting from the handle and operatively engageable with an edge portion of a can engaged by the piercing member, a guard disposed above the piercing member in the use position of the opener and projecting laterally and forwardly beyond the piercing member to block any liquid upspurting from the opening formed by the piercing member,

and a tongue formed integrally with the guard and integrally formed with a pair of opposed lugs bent to engage opposed edges of the handle, said edges being notched to accommodate such lugs.

9. A container opener comprising a piercing member, a fulcrum member and a guard member, and a handle carrying all of said members, the piercing member projecting to one side of the handle and the guard being carried at an opposite side of the handle and being so opposed to the piercing member as to block any jet of liquid spouting from an opening formed by the piercing member.

10. The combination with a container opener having a piercing member, of a guard attached to the opener and so opposed to the piercing member as to block any liquid spouting from a container opening produced by the piercing member, the guard being bodily angularly movable on the opener to maintain contact with a pierced wall of a container as the piercing member enters the container.

11. A can opener comprising: a piercing point, a splash guard hinged over and covering said piercing point, and a handle whereby to operate said opener.

12. A can opener comprising: a piercing point, a splash guard hinged over and covering said piercing point, a handle whereby to operate said opener, and means for keeping said guard pressed toward said piercing point.

13. A can opener of the one stroke rocker type comprising: a piercing portion provided with a hook which engages the rim of the can and serves as a fulcrum around which the piercing point swings, and a splash guard hinged to said piercing portion near said hook.

14. In combination, a can opener having a portion adapted to be pressed against the top of a can to rupture the metal thereof, and a substantially cup-shaped member detachably connected to the can opener and adapted to encircle that portion of the can to be ruptured.

15. The combination with a container opener comprising a handle having a downwardly bent end portion terminating in a piercing point and having a downwardly bent, fulcrum-forming lug adjacent to the bend of said end portion, of a splash guard disposed above the piercing point and attached to the container opener adjacent to said lug.

16. The combination with a container opener comprising a piercing member, a handle carrying the piercing member, and a fulcrum member carried by the opener, the opener having oppositely notched edges, of a splash guard disposed above the piercing member and having a portion attaching it to the opener and engaged in the opposed notches of the opener, and thereby restrained from shifting lengthwise of the opener.

17. The combination with an elongated container opener terminally formed with a piercing point and provided with a fulcrum member between its ends, of a splash guard disposed above the piercing point and having an opening loosely receiving the opener, and thereby afforded an angular motion relative to the opener.

18. The combination with a unit comprising an interconnected container-piercing member and a splash guard, the piercing member being disposed beneath and downwardly projecting from the guard, of a fulcrum member for the unit engaging the unit in proximity to the interconnection of the piercing member and guard.

19. A container opening unit comprising a sub-

stantially circular splash guard having a tongue peripherally projecting therefrom, a piercing member disposed beneath and downwardly projecting from the splash guard, said guard and 5 piercing member being connected as a unit and fulcrum means for the unit arranged beneath said tongue.

20. The combination with an elongated container opener terminally formed with a piercing point and provided with a fulcrum member between its ends, of a splash guard attached to the opener between the ends of the opener, and projecting freely above the opener, toward and beyond the piercing point.

21. The combination set forth in claim 20, the splash guard being yieldable on the opener, and thus adapted to bear on a can top as such top is pierced by said point.

22. The combination with a container opener 5 having a fulcrum member and a piercing point, and angularly movable about the fulcrum member to apply the point to a container, of a splash guard disposed above the piercing point and having a pivotal connection with the container opener, adapting said guard to seat upon a container 10 during functioning of the opener.

WALLACE E. CROSS.
